UNITED STATES PATENT OFFICE.

NELLIE Y. HAMILTON, OF WALWORTH, NEW YORK.

DESIGN FOR A SOFA-PILLOW COVER.

SPECIFICATION forming part of Design No. 36,272, dated March 31, 1903.

Application filed May 21, 1902. Serial No. 108,439. Term of patent 7 years.

To all whom it may concern:

Be it known that I, NELLIE Y. HAMILTON, a citizen of the United States, and a resident of Walworth, in the county of Wayne and State of New York, have invented a new, original, and ornamental Design for a Sofa-Pillow Cover, of which the following is a specification, reference being had to the accompanying drawing, forming part thereof.

10 The drawing is a plan view of a sofa-pillow cover, showing my new design.

As shown in the drawing, the leading or material feature of my design consists of two gaming-dice bodies, with appropriate playing-card heads and feet composed of the spade-symbols used in playing-cards. The dice are shown upon a conventional representation of a diamond spot of a playing-card, ornamented in three of its corners with the club-symbol

20 of a playing-card and in the fourth and lower corner with a pipe having smoke arising therefrom. The combination of the diamond, the ornaments thereon, and the dice-bodies, as described, is established upon a card-cloth ground having in two of its diagonally opposite corners representations of conventional red, white, and blue poker-chips.

25 Having described my invention, what I claim as new, and desire to secure by Letters Patent, is—

30 The ornamental design for a sofa-pillow cover, as herein shown and described.

In testimony whereof I have affixed my signature in presence of two witnesses.

NELLIE Y. HAMILTON.
